SWITCH FOR PRECISE OPERATING LIMITS

William F. Carr, Grand Rapids, Mich., assignor
to Lear, Incorporated, Grand Rapids, Mich., a
corporation of Illinois

Application February 2, 1950, Serial No. 141,992

9 Claims. (Cl. 200—31)

1

This invention relates to electrical switch mechanism. More specifically the invention has reference to such mechanism in which the switch proper is of the over-center snap-action type.

Switches for making and breaking an electrical circuit and incorporating rapid opening and closing of the contacts by virtue of over-center spring action are well known. These may take any of several forms but all have one feature in common, namely the inclusion of a resilient element so arranged as to provide a toggle action, and by means of which a predetermined storage of energy in the spring is released for actuation of a movable contact upon movement of the switch operating element past a dead center.

Such switches are characterized however by a dead zone. That is to say, a portion of the movement of the operating element must be utilized to store energy in the spring so that it becomes impossible to open or close the contacts immediately upon the application of force to the element. In many applications of such switches as a limit switch it is important that opening or closing of the contacts be effected at that same position of the switch operating mechanism at which the contacts had formerly been closed or opened. For example, if such mechanism were to rely upon a rotary cam for such actuation, movement of the switch from "closed" to "open" is desirably effected at the same angular position of the cam in order that a switch opened at say "zero" angular position of the cam shall be closed at another angular position not more than a maximum number of degrees from "zero," say $\pm 1^\circ$.

Heretofore operation of the foregoing accurate character has been unavailable, the best prior arrangement known to me requiring a rotation of the cam on the order of 5° to 10° because of the inherent dead zone or backlash action of the best over-center snap-action switches available.

Accordingly a principal object of the invention is the provision of mechanism for actuating a switch of the over-center snap-action type wherein the above-noted undesirable effects of dead zone are eliminated.

Another object resides in providing mechanism as aforesaid readily adaptable to the mounting of various styles of such switches.

A further object is to provide mechanism as aforesaid in which the switch is carried on a novel form of adjustable mounting.

Other objects will become apparent as the description proceeds.

In the drawing which illustrates one form in

which the invention may be embodied in practice:

Fig. 1 shows a front elevation of the mechanism;

Fig. 2 shows a rear elevation thereof;

Fig. 3 is a cross-sectional view taken along the line 3—3 of Fig. 1;

Figs. 4 and 5 are detail views showing the operation; and

Fig. 6 is a diagrammatic view to assist in the explanation of the words "dead zone" as employed herein.

At the outset it will be understood that the invention mechanism is capable of manifold applications. By way of example the same will be described as deriving operation from a rotary cam, as may be the case in certain types of electric motor driven rotary actuators for aircraft components, and in which installations the current to the motor is to be interrupted upon a predetermined angular positioning of the output shaft following motion in one direction and re-established upon rotation of the shaft in the opposite sense. As noted, it is preferred that reclosing of the switch be effected in as nearly the same angular position occupied by the cam at the moment the switch was opened.

Referring first to Figs. 1, 2 and 3, there is shown a suitable support, e. g., a plate 10 in which a shaft 11 is journaled for rotation. At its forward end shaft 11 has a switch operating cam 12, sometimes herein referred to as the main cam, secured thereto, as by a nut 13. Shaft 11 is adapted to be rotated by power means (not shown) which may be by means of reduction gearing driven by an electric motor, and to be pointed out hereinafter. In any case it will be understood that main cam 12 is rotated at a relatively low rate of speed, as would be required for reliable actuation of a limit switch, in order to avoid errors of over-travel incident upon operation at too high a speed.

Also journaled for rotation in plate 10 is another shaft 15 upon which is secured, as by a screw 16, an eccentric cam 17, sometimes herein referred to as the auxiliary cam. In accordance with the principles of the invention the cam 17 is adapted for rotation at a speed substantially higher than that of the cam 12, say 100 times as fast. Secured to a shaft 18 driven by the power source is a pinion 25 in mesh with gear 21 keyed to cam shaft 11. Also keyed to shaft 11 is a pinion 22. Increased speed for the eccentric 17 is attained by meshing pinion 22 with a gear 23, which in turn meshes with pinion 24 secured to eccentric shaft 15.

The snap-action switch 31 may be of any well-known type, and is shown exemplificatively as comprising an insulating support 32 in which a pair of rigid contact members 33 and 34, a movable resilient center contact 35, an actuating arm 36 and the U-shaped resilient toggle spring 37. Such switch is of the type disclosed in U. S. Letters Patent No. 2,237,705, granted April 8, 1941, so that further elaboration of details of construction and functioning is deemed superfluous. The several switch elements are embedded or otherwise carried in support 32, which latter is secured to a pivoted or oscillable bracket 41 shortly to be described. It will be noted that switch arm 36 bears on the surface of cam 12 for joint operation by a rise portion 38 of the latter and by the cam 17, and in a manner to be pointed out.

Pivoted on a shoulder screw 43 set into the support plate 10 is the swingable mounting plate 44 comprising a body portion 45, and an out-turned flange 46 which, for portions of its length, continues parallel to the body 45 to form a retaining lip 47 for the oscillable switch body 32 and a second outturned flange 48 providing, together with the body 45 parts having apertures for engagement over the screw 43. A nut 49 is swaged into the upper end of the flange 46 and receives an adjusting screw 51 passing through an aperture in an outstanding projection 52 of the plate 10. Thus by rotation of screw 51 the plate 45 may be hinged about the pivot 43 thereby to move the bracket 41 and hence the switch 31 toward and away from the cam 12 for adjustment of the relationship therebetween. Such selected adjustment may be rendered semi-permanent by lock nut 54.

Bracket 41 is arranged for pivotal movement with respect to plate 45 by supporting the same on a pivot screw 56 secured in the plate 45 and passing through an aperture in the lip 47, a nut 57 in turn locking screw 56 in place. A bolt 61 is employed to attach the switch body 32 to the bracket 41, the opposite end of the body 32 likewise being apertured for clearance of pivot screw 56. An outturned ear of the bracket 41 is adapted to serve as a follower 62 for the auxiliary cam 17, and a spring 63 secured to follower 62 and to a post 64 in the plate 10 biases bracket 41 constantly in a counter-clockwise sense about its pivot 56. Thus rotation of cam 17 is effective to rock the switch 31 to and fro about the pivot 56 at a rate proportional to the angular velocity of the cam 12 and as determined by the ratio of the speeds of the shafts 11 and 15.

Prior to describing the operation of the invention mechanism it is believed that the same will be clarified by reference to Fig. 6. Such schematic showing represents somewhat generally an over-center snap-action switch 71, including parts as described in connection with Fig. 1, and having an actuating button 72, which latter may be regarded as being secured to the switch arm 36 within the casing. The free position of the button 72 is shown in full lines and represents one position of the several switch elements, for example, a set of contacts 33 and 35 being then regarded as closed. Assuming pressure is applied to the button 72 energy is stored in the spring 37 until a position is reached whereat the movable switch element 35 trips to the right. The end face of the button is now at the dotted line designated "tripped position." To reverse the position of the element 35 the button is now released. However due to the toggle action, the element 35 is not moved simultaneously with reverse movement or release of the button, such reverse movement

of the element 35 not occurring until a button position designated "Reset position" is reached. The delay between "tripping" and "reset" is defined as the dead zone, and, if actuation of the switch arm 36 is the result of rotary cam action, such dead zone would correspond to several degrees of rotation of the cam, and consequent inability to open and close the switch at substantially the same angular position of the cam.

Referring now to Fig. 4 the switch 31 is shown with element 35 against contact 33 so that the circuit represented thereby is closed. In the absence of the improvement of this invention the cam rise, after effecting opening of the contacts 33 and 35, would have to be backed off or reversed from 5° to 10° before the contacts could close again, this angular distance representing the dead zone.

With the invention improvement operation is as follows: Assuming that rise portion 38 has arrived, say in a counter-clockwise sense, into first contact with arm 36. However, since a finite amount of rotation is required to trip the switch, corresponding to a change in the radially spaced points of the cam rise surface, the switch unit 31 is not maintained stationary, awaiting such amount of rotation, but is moved against the cam in what may be termed a "feeling" action. Such action is brought about by the auxiliary cam 17.

Assuming a speed of main cam 12 of 1 R. P. M. the auxiliary 17, in the example, will have a speed of 100 R. P. M. Such rotation of cam 17 will oscillate the entire switch 31 about the pivot 56, and the switch arm 36 is seeking to contact the cam 12. It will be understood that both cams are rotated jointly, and that consequently the first contact of rise 38 with switch arm 36 will occur while the switch is being oscillated. Upon first contact of switch arm and cam the switch is not tripped because the dead zone still exceeds the movement of the switch arm corresponding to the eccentricity of the cam 17. Upon the next revolution of the cam 17 the point of trip is approached more closely due to advance of the cam rise 38. After the foregoing cycle has been repeated several times the trip is realized and the switch is finally actuated since the eccentric 17 has been continuously oscillating, the switch bracket 41, and the rise 38 on cam 12 has slowly advanced to a position whereat the dead zone has been overcome. Should the cam 12 now be reversed from the point at which switch closure had just been effected, the eccentric 17 likewise reverses to move the switch arm with respect to the cam 12 to break the circuit at once.

Inasmuch as the speed ratio between cams 12 and 17 is, in the example, 100 to 1, very little motion of the cam 12 is required to open the contacts. On the second reverse turn of the cam 17 the contacts can not be re-closed since the cam 12 has reversed far enough to prevent a trip.

The setting of the mechanism for the amount of dead zone individual to a selected switch may be effected by selection of the speed ratio between the cams 12 and 17.

Assuming a ratio of 100 to 1 between the rotational velocities of the cams 12 and 17, one-half a revolution (180°) of the eccentric, i. e., from minimum radius to maximum radius, will correspond to 1.8° on the cam 12. Accordingly while cam 12 is rotating 1.8° the bracket 41 is being swung one complete reciprocation. The arrangement is such that with a predetermined relation of the cam rise (represented by line A) to the arm 36, one reciprocation of the bracket will trip the switch, and vice versa, one reciprocation will

upon reverse movement of the cam 12, reset the switch. Thus, with the speed ratio herein assumed, dead zone is made not more than 1.8°. It will be obvious that with ratios greater than 100 to 1, greater angular accuracy may be achieved.

While for completeness in the description the switch 31 has been depicted as of the single pole-double throw type, the operation has been described for only one side thereof. It will be obvious that with the arrangement shown opening of contacts 33 and 35 will result in closing of contacts 34 and 36 and vice versa, but, in either event, with the advantages of the invention mechanism. Moreover that a single cam 12 may actuate more than one switch provided that each is arranged for oscillatory action as described. For example a second switch assembly and bracket may be located to the right of the vertical center line of the cam 12 (as seen in Fig. 4), symmetrically with the eccentric 17, and actuated by that eccentric.

While I have shown a particular embodiment of my invention, it will be understood, of course, that I do not wish to be limited thereto since many modifications may be made, and I therefore contemplate by the appended claims to cover any such modifications as fall within the true spirit and scope of my invention.

Having thus described my invention, what I claim and desire to secure by Letters Patent is:

1. Mechanism for actuating an electrical switch of the over-center snap-action type having an actuating element comprising a main cam, an auxiliary cam, means for rotating said cams jointly, said means being arranged to provide a speed for said auxiliary cam substantially higher than the speed of said main cam, a support for said cams, a bracket oscillatably carried on said support and including means for mounting the switch thereon, the actuating element of the switch being positioned for operation by said main cam, and a follower forming part of said bracket and in operative relation with said auxiliary cam.

2. Mechanism as recited in claim 1 in which said main cam includes at least one rise portion, and said auxiliary cam is a simple eccentric.

3. Mechanism as recited in claim 1 in which said cam rotating means includes a power source and gearing interconnecting said cams.

4. A switch mechanism comprising a support, a bracket oscillably carried on said support, an over-center, snap-action electrical switch having an actuating element and secured to said bracket, a rotatable main cam, said element being disposed in operative relation with said cam, a rotatable auxiliary cam, means for driving said cams joint-

ly at different speeds, said support having a follower portion in operative relation with said auxiliary cam, each said cam having at least one active rise portion, and said driving means being so arranged as to cause said auxiliary cam rise portion to oscillate said support at a rate substantially greater than the rate at which said main cam rise actuates said switch element.

5. Mechanism as recited in claim 4 in which said main cam is provided with a single rise and said auxiliary cam is a simple eccentric.

6. Mechanism as recited in claim 4 in which said cam driving means comprises a power source and gearing interconnecting said cams.

15 7. A switch mechanism comprising a support, a bracket oscillably mounted on said support, an over-center, snap-action switch secured to said support, said switch having an actuating element, a rotatable main cam having at least one rise, said element being adapted for contact with said cam, a rotatable auxiliary eccentric cam, means for rotating said cams jointly, said bracket having a follower portion in contact with said auxiliary cam, said rotating means being so arranged as to cause said auxiliary cam to oscillate said bracket a substantial number of cycles during the period when said main cam rise is rotated over substantially half its angularly active portion.

20 8. Mechanism as recited in claim 7 in which said cam rotating means comprises a power source and gearing interconnecting said cams.

25 9. A switch mechanism comprising a support, a bracket oscillably mounted on said support, an over-center, snap-action switch secured to said support and including a actuating element, a rotatable main cam having a rise portion in operative relation with said element, a rotatable auxiliary cam comprising a simple eccentric configuration, said bracket having a follower in operative 30 relation with said auxiliary cam, power means for rotating said cams jointly, and gearing operatively connected to said power means and cams for rotating said auxiliary cam at a speed substantially in excess of that of said main cam.
